(57) **CLAIM**

The ornamental design for a latch for a container and lid, as shown and described.

DESCRIPTION

FIG. 1 is an enlarged left front side perspective view of a container and lid latch showing my new design, the right side being identical to the left;

FIG. 2 is a front view thereof;

FIG. 3 is a reduced scale left side view thereof;

FIG. 4 is a right side view thereof;

FIG. 5 is an enlarged top plan view thereof;

FIG. 6 is a left side cross-sectional view taken along line 6—6 of FIG. 1; the right side being identical to the left side;

FIG. 7 is a reduced scale left front side perspective view of the latch for a container and lid, showing my new design; the right side being identical to the left side, the container and lid shown in broken line for environmental purposes;

FIG. 8 is an enlarged left front side perspective view of the latch for a container and lid, showing my new design, in a partially open state; the right side being identical to the left side;

FIG. 9 is a left side view thereof, the right side being identical to the left side; and,

FIG. 10 is a reduced scale left front side perspective view of the latch for a container and lid, showing my new design, in a partially open state; the right side being identical to the left side, the container and lid shown in broken line for environmental purposes.

The broken line showing of a container is included for the purpose of illustrating environment and forms no part of the claimed design. The bottom view has no ornamental features other than those shown and described.
